Primary Examiner — Phillip S Hyder(74) *Attorney, Agent, or Firm* — Blakely Sokoloff Taylor Zafman LLP(57) **CLAIM**

The ornamental design for a multi-rail abdomen exerciser, as shown and described.

DESCRIPTION

FIG. 1 is a perspective view showing the new design for an multi-rail abdomen exerciser;

FIG. 2 is an enlarged front view thereof;

FIG. 3 is an enlarged rear view thereof;

FIG. 4 is an enlarged right side view thereof;

FIG. 5 is an enlarged left side view thereof;

FIG. 6 is an enlarged top view thereof; and,

FIG. 7 is an enlarged bottom view thereof.

The broken lines depict portions of the multi-rail abdominal exerciser in which the design is embodied that are not considered part of the claimed design.
